(57) **CLAIM**

The ornamental design for a ceiling fan with light fixture, as shown and described.

DESCRIPTION

FIG. 1 is a perspective view of a ceiling fan with light fixture embodying my design;

FIG. 2 is a front view of the ceiling fan with light fixture; FIG. 3 is a rear view of the ceiling fan with light fixture; FIG. 4 is a top view of the ceiling fan with light fixture; FIG. 5 is a bottom view of the ceiling fan with light fixture; FIG. 6 is a left side view of the ceiling fan with light fixture; and,

FIG. 7 is a right side view of the ceiling fan with light fixture.

The broken lines are shown for the vent holes on the top of the fan housing, for the top sides of the blade arms, and for the outward ends of the blade arms to which the fan blades are mounted in FIGS. 2 through 4, 6, and 7. None of the broken-line matter forms a part of the claimed design.
